WATER HEATING AND CIRCULATING APPARATUS.

APPLICATION FILED AUG. 29, 1905.

Fig. 1.

UNITED STATES PATENT OFFICE.

PETER J. KOLICH, OF OAKLAND, CALIFORNIA.

WATER HEATING AND CIRCULATING APPARATUS.

No. 833,466.

Specification of Letters Patent.

Patented Oct. 16, 1906.

Application filed August 29, 1905. Serial No. 276,239.

To all whom it may concern:

Be it known that I, PETER J. KOLICH, a citizen of the United States, residing at Oakland, in the county of Alameda and State of California, have invented new and useful Improvements in Water Heating and Circulating Apparatus, of which the following is a specification.

My invention relates to an apparatus which is especially designed for heating, circulating, and distributing water.

It consists in the combination of boiler-heating coils, distributing and return pipes, and in details of construction which will be more fully explained by reference to the accompanying drawings, in which—

Figure 1 is a vertical section through my apparatus. Fig. 2 is a reduced plan view of the coils.

As shown in the drawings, A is a support upon which the extension B of the preliminary water-receiver 2 is carried. This portion is adjustably supported in any suitable or desired manner from the part A. The lower receiver 2 is here shown as being concavo-convex in form, and water is delivered into it from any source of supply under pressure through a pipe 3. Water rises from the part 2 through a plurality of hollow legs, as shown at 4, and thence it passes into two horizontally-disposed superposed coils 5 and 5^a. The water enters the outer convolutions of the coils and passes inwardly through the decreasing coils, and at the center the two inner ends of the coils 5 and 5^a unite, and through a pipe 6 the water is delivered into the lower part of the boiler 7. This pipe 6 is closed at the top and may have openings 6' near the bottom in its sides, through which water may escape into the boiler, as shown by the arrows. The water is thus introduced into the lower part of the boiler with its temperature somewhat raised by a heater of any suitable description located beneath the coils 5 5^a and another series of coils, to be hereinafter described, and all contained within the casing surrounding the lower part of the apparatus. A heater of this description may be illustrated, as at 8. The water entering and passing up through the legs 4 and up through coils 5 5^a is thus heated somewhat and enters the boiler, as previously described, where it is still subjected to further heat, and the hot water constantly ascending displaces the cooler water and rises

to the top of the boiler. From this point the water is taken through a distributing-pipe, as at 9, and passes therethrough, having branches which may pass to the kitchen boiler or sink and to radiators by which rooms are heated and bath-rooms and other offices of the house. 10 is a pipe also opening out of the top of the boiler, but extending down into the boiler to a point considerably below the top and into the space occupied by the cooler water. Above the mouth of this pipe the hottest of the water will be found and is drawn from the boiler, as previously described. Through the pipe 10 the cooler water arises, passing through a connecting-pipe, as at 11, and through a T or cross 12 is returned into a double superposed horizontal coil 13.

By means of a pipe 14 the water which has been distributed from the upper part of the boiler through the radiators, as previously described, is also returned and passes through the cross or coupling 12 and into the heating-coil 13. The water passing through this coil from the outside reaches the center and through the connection 13^b extends vertically into the other part 13^a of the coil, whence it passes outwardly around this coil, still subjected to the heat of the fire below, and is eventually delivered outwardly through a pipe 15, which conducts it upwardly and delivers it into the upper part of the boiler, which is thus constantly supplied with hot water, and this water lies above the mouth of the intake-pipe 10 and may be discharged at any time outwardly through the pipe 9, as previously described. The water within the boiler is thus subjected to a progressive heating.

Surrounding the boiler is a jacket, which is composed of double walls, as shown at 16, and the inner wall may be lined with asbestos, so that the whole apparatus is incased with this non-conducting surface and the exterior remains cool. The heat from the fire or burner passing up through the space between the wall 16 and the outside of the boiler 7 provides an additional heating-jacket for the boiler. The top of the jacket 16 closes over the space above the boiler, and within this top is made a concave portion, as shown at 7^a, approaching the top of the boiler near the center. Through this intermediate space the heat products are carried to the center, where there is a discharge-opening, 110

as at 17. Through this opening the products of combustion escape from the jacket and thence pass into a chamber above the jacket, as at 17^a, eventually escaping therefrom through a discharge pipe or passage, as at 18, and to the chimney. This jacket 16 is preferably formed with an open seam at its meeting edges, and it may be provided with hooks and engaging staples or equivalent fastening devices, as shown at 19, so that it can be detachably secured together and easily removed for the purpose of obtaining access to the interior for cleaning or other purposes.

A transparent mica door 20 may be fixed in the side of the casing opposite the heating apparatus, so that the latter can be readily inspected.

Having thus described my invention, what I claim, and desire to secure by Letters Patent, is—

1. The combination in a water-heater, of a boiler, a hollow base, means for supplying water thereto, upwardly-extending water-legs in communication with the base, superposed coils, said coils each having its outer convolution connected with one of said water-legs, and means for providing direct communication between the coils and between said coils and the lower part of the boiler.

2. The combination in a water-heater, of a boiler, a hollow base, upwardly-extending water-legs in communication with the base, means for admitting water to the base, superposed coils, means for providing direct communication between the inner ends of the coils and between the coils and the boiler, each of said coils having its outer end connected to one of the water-legs.

3. The combination in a water-heater, of a hollow base having upwardly-extending water-legs, means for supplying water to said base, a coil having superposed reversely-arranged convolutions, one of said convolutions being in communication with one of the water-legs, and the other convolution being in communication with the other water-leg, and means for providing direct communication between the convolutions of

the coil and between said coil and the bottom portion of the boiler.

4. The combination of a boiler, a hollow base, means for supplying water to said base, upwardly-extending water-legs in communication with the base, superposed coils, the lower of which is in communication with one of said water-legs, the upper coil being in communication with the other water-leg, means for providing direct communication between the coils and between said coils and the lower part of the boiler, a coil below the first-named coils, circulating-pipes connecting with opposite ends of the second-named coil, one of said pipes leading from said second coil into the upper part of the boiler, and the other circulating-pipe leading from the boiler into the receiving end of the second-named coil, and a heater in said base below the second-named coil.

5. The combination of a boiler, a hollow base, means for supplying water to said base, upwardly-extending water-legs in communication with the base, superposed coils one of which is in communication with one of said water-legs, and the other of which is in communication with the other water-leg, means for providing direct communication between the coils and between said coils and the lower part of the boiler, a second coil below the first-named coils, a pipe leading from the boiler into the receiving end of the second-named coil, a pipe leading from the delivery end of the second-named coil into the upper portion of the boiler, a heater below the first and second named coils and the boiler, and a water distributing and return system of pipes connecting with the upper part of the boiler, and having the return-pipe of said system connecting with the inlet to the second-named coil.

In testimony whereof I have hereunto set my hand in presence of two subscribing witnesses:

PETER J. KOLICH.
